CLAIM

The ornamental design for a steering wheel having pedal stand, as shown and described.

DESCRIPTION

FIG. 1 is a first side view of a steering wheel having pedal stand;

FIG. 2 is a second side view of the steering wheel having pedal stand shown in FIG. 1;

FIG. 3 is a front view of the steering wheel having pedal stand shown in FIG. 1;

FIG. 4 is a rear view of the steering wheel having pedal stand shown in FIG. 1;

FIG. 5 is a top view of the steering wheel having pedal stand shown in FIG. 1;

FIG. 6 is a bottom view of the steering wheel having pedal stand shown in FIG. 1;

FIG. 7 is a first rear, upper perspective view of the steering wheel having pedal stand shown in FIG. 1;

FIG. 8 is a second rear, upper perspective view of the steering wheel having pedal stand shown in FIG. 1;

FIG. 9 is a first forward, upper perspective view of the steering wheel having pedal stand shown in FIG. 1;

FIG. 10 is a second forward, upper perspective view of the steering wheel having pedal stand shown in FIG. 1;

FIG. 11 is a first rear, lower perspective view of the steering wheel having pedal stand shown in FIG. 1; and,

FIG. 12 is a first forward, lower perspective view of the steering wheel having pedal stand shown in FIG. 1.

In the drawings, the broken lines in the drawings illustrate environmental subject matter and form no part of the claimed design.
